UNITED STATES PATENT OFFICE

OMER FRANÇOIS LEFEBVRE, OF MONTREAL, QUEBEC, CANADA

STAMP CANCELING MACHINE

Application filed June 22, 1928. Serial No. 287,514.

The present invention relates to improvements in stamp canceling machines for the purpose of simultaneously canceling the stamps upon mail matter and indicating thereon the name of post-office, the date year and other desired information.

The main object of the invention is to provide a simple and effective machine of the character described to uniformly, effectively and quickly cancel the stamps on mail matter.

Another object of the invention is to provide a machine of this character, that will indifferently cancel the stamps on mail matter of different size and thickness.

15 A further object of the present invention is to provide a machine in which the canceling operation begins intermediate of the length of the postal matter and extends towards the edge thereof, thus providing for 20 uniformity of printing.

The invention is hereinafter fully described and claimed and is illustrated in the accompanying drawings, in which:

Figure 1 is a top plan view of a stamp canceling machine embodying the invention.

Figure 2 is a side elevation view of the same.

Figure 3 is an enlarged fragmentary top plan view of the machine in its non-printing 30 position.

Figure 4 is a similar view to Figure 3, showing the machine in the position when it begins printing.

Figure 5 is an enlarged fragmentary underside plan view of the means for controlling or timing the printing operation.

Figure 6 is an enlarged top plan view of the printing roller stamp.

Figure 7 is a longitudinal section on line 40 7-7 of Figure 5.

Figure 8 is a top view of the roller stamp, the cover or lid having been removed to disclose the inner mechanism when the stamp 45 units are in their locked position.

Figure 9 is a similar view to Figure 8, illustrating the stamp units in their unlocked position so that they may be removed.

Figure 10 is a side elevation view of Figure 50 6.

Like numerals of reference indicate corresponding parts in each figure.

Referring to the drawings, 1 designates a base plate to support the mail matter and mounted on the brackets 2 on the casing 3, in 55 which is located the gear train, said casing being supported upon the base 4 in which may be located the electric motor 5. Upon said base plate 1 is provided a vertical wall 6 located adjacent one end and the vertical walls 60 7 located adjacent the opposite end of said base. Adjacent the wall 6 is provided the space 8 upon which the mail matter is placed, for feeding into the machine said space being closed on one side by the aforesaid walls 6 65 and on the other side by the diagonal wall 9 and 10 are a plurality of parallel and diagonal sharp ribs upon which the said mail matter engages, to insure for an even and regular feeding to the machine and preventing 70 the mail matter from backing the wall 9.

Projecting through the suitable openings in the wall 6 are provided the feeding rollers 11 and 12, said feeding roller 12 being preferably covered with rubber, and is mounted 75 opposite the feeding flexible fingers 13 which are resiliently mounted upon the crank levers 14 fulcrumed at 15 and held in operative position by means of the adjustable springs 16.

The mail matter is preferably placed parallel to the wall 6, the piece adjacent the wall being first engaged by the roller 11 and carried in between the feeder fingers 13 and roller 12 which feeds the piece to the driving rollers 18, 19, 20 and 21 which have for 80 purpose the driving of the mail piece to the stamp roller 22 for the canceling operation.

The stamp roller 22 which will be herein-after fully described is provided with a diagonal cut-out portion 23 and 24 is a companion movable pressure roller also provided with a diagonal cut-out portion 25, whereby, when said stamp and pressure rollers are revolved, as disclosed in Figure 3 of the drawings, a 95 gap or space 26 is provided, in order that the mail piece 17 may freely pass therethrough to approximatively mid-way of its length when pressed forward by the driving rollers, before being engaged by said stamp 100

and pressure rollers 22 and 24 and the stamping and cancellation begins.

Adjacent said stamp and pressure rollers 22 and 24 are provided the guiding rollers 27 and 28 whose object is to carry the mail piece 17 after being canceled onto the stacker 29. Suitable guideways 30 and 31 are also provided between the rollers to eliminate the crumpling of the mail pieces. The roller 28 is preferably mounted on the flexible support 32.

The stamp roller which is mounted upon the stamp shaft 33 is controlled by the timing finger 34 which is located between the rollers 18 and 19, and is pressed outwardly by the mail piece as it is pressed forward and remains in this position until the piece has fully passed. Immediately after the said piece leaves the rollers 18 and 19, it disengages the finger 34 which drops into its primary position, which simultaneously actuates the shaft 35 upon which it is mounted and moves the fulcrumed lever 36 spring held at 37. The said lever 36 presses downwardly the pawl-lever 38 which passes through the spring held guiding bracket 39 and is pivotally connected at 40 to one end of the lever 41 which in turn is pivoted at 42.

The end of the lever 41 is bent at 43 to actuate the clutch member 44 mounted upon the stamp shaft 33. The lever 41 is thus actuated by means of the dent or pawl 45 which, when the lever 38 is pressed downward by the lever 36, engages the ratchet 35 wheel 46 mounted upon the shaft 47. The movement imparted to the lever 41 releases same from contact with the clutch, which causes the drum 48 to come into contact with said clutch to actuate the stamp shaft 33 and stamp roller 22. As it will be readily understood the stamp is operated only after the end of the postal piece 17 has left contact with the timing finger 34, thus insuring a uniform and even stamping and cancellation of the postal matter. On the clutch 44 is provided a roller pin 49 which, upon rotation of said clutch, engages the cam member 50 thereby returning the lever 41 in its primary position and also carrying bent end 43 in engagement with the clutch member. In the bracket 39 is provided a spring 39^a which disengages the pawl-lever 38 from the ratchet wheel 46.

The pressure roller 24 which is preferably mounted on the flexible shaft 51 carried by the spring held bracket 52, is actuated by the stamp shaft 33 by means of suitable gears 53.

The rollers 11, 12, 18, 20, 22 and 27 are mounted on suitable shafts actuated by a suitable gear train 54 mounted in the casing 3 and actuated by the pulley 54^a which is suitably connected to the motor 5. The rollers 19 and 21 are mounted upon the flexible spring held supporting bracket 55.

35 The stamp roller 22 is provided with the

side walls 56 and top and bottom plates 57. One side of said roller is flat and open at 58, and 59 is one or more suitable openings in which are located the removable stamp units 60 and 61. The said stamp roller is provided with a stub-shaft 62 upon which is mounted the stamp unit support 63 and on one side thereof is provided a plate 64 having a hook portion 65 adapted to engage a recess 66 in one of the stamp units 60.

The open portion 58 of the stamp roller is preferably closed by the plate 67 which is hinged at 68 and spring held at 69, so as to normally close said door or plate 67. When said plate 67 is closed, a lug 70 thereon is made to engage a corresponding recess 71 in the side of the stamping unit. It will therefore readily be understood that when the plate 67 is closed, the stamp units 60 are locked in their respective position, and when said door or plate 67 is opened, the locking lug 70 is disengaged from the recess and thereby unlocks the said stamp unit for the purpose of removing them to change the hour, date and month whenever necessary. The stamp unit 61 is preferably fixed by means of the screw 72. As the stamp bears the year, it is supposed to be changed only from year to year, and therefore does not require a fastening means that is quickly unlocked.

The stamp roller is provided with a projecting tubular portion 73 which engages upon the end of the shaft 33 and is suitably locked thereon by means of the pin 74, said shaft 33 imparting a suitable rotation to the stamp roller.

In the operation of the present invention it is desired to point out that a new method is employed in canceling postal-matter. One well known method consists in providing a "stop" which controls or holds the postal-matter at its end until such time as the postal-matter already in the machine, has been duly canceled. This method is most irregular because of the difficulty in adjusting said stop, which can hardly be depended upon. In the present invention it is the postal-matter which controls the "timing finger", said timing finger being released to operate the stamp roller, only when the postal matter is in its proper position for cancellation. It also places all the postal matter which may be of any thickness or size in identically the same position, so that cancellation will be the same on all, thus providing uniformity as well as precision.

The aforesaid described machine is only a preferred form of my invention, but it must be understood that I reserve the right to make any modification thereto, providing these modifications fall within the scope of the following claims of novelty.

What I claim as my invention is:

1. A stamp canceling machine consisting of a stamp roller and a pressure roller and

means to automatically stop said rollers until the rear end of postal matter fed thereto passes a predetermined point.

2. A stamp canceling machine consisting of a stamp roller and a pressure roller, means to automatically stop said rollers while feeding postal matter of varying length thereto and means controlled by said postal matter to actuate said rollers, so as to print on said postal matter from an intermediate portion to one end thereof, substantially as described.

3. A stamp canceling machine consisting of a stamp roller and pressure roller each having a cut-out portion in its periphery, means to automatically stop said rollers whereby a space is provided therebetween, means to feed postal matter between said rollers, and means to actuate said rollers to cancel said postal matter, said means being controlled by said postal matter and held in inoperative position during such time as said postal matter contacts therewith, substantially as described.

4. In a stamp canceling machine, a printing roller, means for feeding matter of varying lengths to said roller, and means whereby said roller begins to print intermediate the length of said matter and continues to one end thereof.

5. In a stamp canceling machine, a printing roller, an impression roller, and means controlled by the rear end of matter passing through said rollers to control said rollers to cancel postal matter passing therethrough.

6. In a stamp canceling machine, a printing roller, means for feeding matter to said roller, and means whereby said roller prints from a point intermediate the length of said matter towards one end thereof, said means being controlled by the rear end of matter being fed to said rollers.

7. In a stamp canceling machine, means for printing on matter of varying lengths passing through said machine, and means whereby said machine begins to print intermediate the length of said matter and continues to the rear end thereof.

8. In a stamp canceling machine, a printing roller, an impression roller, a member adapted to be depressed by matter passing through the machine to prevent the turning of said rollers, said member being adapted upon the passage thereby of the end of said matter to permit the rotation of said rollers.

9. In a stamp canceling machine, a printing roller, an impression roller, means for feeding matter to said rollers, a member in the path of said matter adapted to be deflected thereby, said member being normally resiliently urged into the path of said matter, and means whereby the deflection of said member prevents operation of said rollers, while the return of said member to normal position permits the operation of said rollers.

10. In a stamp canceling machine, means

for printing on matter of varying lengths passing through said machine, and means for beginning the printing operation a constant distance from the rear end of the matter and continuing toward one end thereof.

11. In a stamp canceling machine, a printing roller, an impression roller, means adapted to stop said rollers, means contacting with said postal matter, said means causing said rollers to be released and revolved upon leaving contact with the postal matter.

Signed at Montreal, Quebec, Canada, this 19th day of June, 1929.

OMER FRANCOIS LEFEBVRE.
